UNITED STATES PATENT OFFICE

2,652,869

MULTISECTION VENEER KNIFE

Clarence Goodman, High Point, and Claud T. Miller, Hickory, N. C.; said Miller assignor to said Goodman

Application June 11, 1951, Serial No. 231,032

1 Claim. (Cl. 144—241)

1 This invention relates to an improved multi-section veneer knife and more especially to that type of veneer knife which is adapted to be associated with a veneer shaving machine wherein the knife is positioned in the machine and is moved automatically by said machine toward a revolving log to cut a thin strip from about the periphery of said log to form veneer sheets.

Heretofore in using knives of this type a solid knife, the length of the log, has been utilized and such a knife would rapidly wear and cause irregularities in the veneer sheet being stripped from the log which would require frequent replacement. It is therefore an object of this invention to provide a veneer knife having a beveled edge and the tip portion of the same being cut away and provided with an insert of hardened material such as tungsten carbide fused to the knife to provide an extremely hard edge which will not wear as rapidly as the knives heretofore in use.

In using a tungsten carbide tip to give increased wear to the veneer knife, it has been found that the heat necessary to braze the tip of the knife would cause warping of the knife and it is therefore another object of this invention to provide an improved knife with a base portion and a plurality of removable sections, each of said sections being relatively short and securable in alignment with each other to the base portion to form a composite knife having a smooth cutting edge extending the entire length thereof.

It is another object of this invention to provide a veneer knife adapted to be associated with a veneer machine for shaving sheets of veneer from a log comprising a base section of substantially the same length as the log to be shaved, a plurality of knife sections of relatively short length, means for securing said knife sections in alignment with each other to said base section, each of said knife sections being beveled to a point, the beveled edge thereof being cut away and provided with a tungsten carbide tip fused therein to present an extremely hard cutting surface, the cutting edge of each of said knife sections being straight and in alignment with the other knife sections to present a straight cutting edge to the composite veneer knife thus formed.

Some of the objects of the invention having been stated, other objects will appear as the description proceeds, when taken in connection with the accompanying drawings in which—

Figure 1 is a top plan view of the improved

2 multi-section veneer knife showing portions of a clamping plate associated therewith;

Figure 2 is a vertical sectional view through the improved veneer knife taken along the line 2—2 in Figure 1;

Figure 3 is an isometric view of one end of the improved veneer knife and associated clamping plates with parts in section;

Figure 4 is an isometric view of the base section of the improved veneer knife with the knife sections removed therefrom;

Figure 5 is an isometric view of one of the knife sections used to make up the multi-section veneer knife;

Figure 6 is a schematic elevation showing the manner in which the veneer knife is clamped between clamping plates for movement toward a revolving veneer log for shaving strips of veneer therefrom.

20 Referring more specifically to the drawings, the numeral 10 indicates the base section of the improved veneer knife which base section may be formed from any suitable material and is substantially planar and is preferably of a length substantially the same as or greater than the length of the veneer log to be shaved. The leading lower surface of the base section 10 is cut away as at 11, the cut away portion 11 extending the entire length thereof, for reception of a plurality of knife sections 12. Each knife section is formed from a hard piece of metal such as steel having a flat upper surface 13, a flat base portion 14 and a beveled edge 15. The upper edge of the knife section 12 remote from the beveled edge 15 is cut away as at 16 to provide a mating groove adapted to mate with the cut away portion 11 of the base section 10 for securing the knife section 12 to the base section 10.

The leading edge of the knife section 12 is cut away as at 20 and inserted in the cut away portion 20 is a tip, cutting edge, or cutting portion 21 of extremely hard material such as tungsten carbide which cutting portion 21 is suitably secured to the knife section 12 as by brazing so that the cutting portion 21 forms an integral part of the knife section 12. The portion of the knife section 12 defined by the cut away portion 16 is provided with at least one but preferably two threaded bores 22 adapted to coincide with bores 23 in the base section 10 to permit a plurality of knife sections 12 to be secured to the base section 10 as by screws 24. The bores 23 are preferably counterbored.

It should be noted that the cut away portion 16 and the cut away portion 11 are preferably

cut at right angles so as to mate perfectly with each other and these cut away portions are finished to exact dimensions so that the upper surfaces 13 of the knife sections 12 will be flush with the upper surface of the base section 10 and each of the knife sections 12 will be in exact alinement to present a smooth cutting edge. The sides of the knife sections 12 are also finished smoothly to permit each of the knife sections to be positioned in close engagement with the corresponding knife section and to eliminate any gaps therebetween so that the cutting portions 21 will cut a smooth sheet of veneer from the veneer log.

In order to properly position the knife sections so as to have them in perfect alinement, it is frequently necessary or advisable to use some type of clamp, not shown, and to this end, the base section 10 may be provided with taps 30 and 31 in the ends thereof to facilitate use of such a clamp.

Now, in using a multi-section veneer knife of the type described, the veneer knife is ordinarily associated with a conventional or other type of veneer machine wherein means are provided for clamping the veneer knife and moving the same automatically toward a revolving veneer log for shaving a layer of material from the veneer log which material may then be used as veneer.

Referring to Figure 6, a schematic illustration is shown of clamping means, which may be associated with a machine of this type for holding the veneer knife in the desired position relative to the veneer log, the clamping means being shown by way of illustration only, it being understood that any suitable mechanism and clamping means may be used. Clamping plates are indicated at 32 and 33 and an illustrative veneer log is shown at 34. The clamping plates 32 and 33 are also shown in Figures 1, 2 and 3 and when using clamping plates of this type, the base section 10 may be provided with one or more bores 36 therein adapted to receive bolts 37 for clamping the plates 32 and 33 against the upper and lower surfaces of the composite multi-section veneer knife. Where the multi-section veneer knife is used with clamping plates which are held together by mechanism other than bolts 37, the bores 36 may be omitted from the base section 10.

It is thus seen that there is provided an improved veneer knife comprising a base section having a right-angular cut away portion extending along the leading edge thereof and a plurality of knife sections, each being cut away and being adapted to be secured to the cut away portion of said base section and each of said knife sections having a hard cutting edge and being

positioned in alinement with each other to form a straight cutting edge.

In the drawings and specification, there has been set forth a preferred embodiment of the invention and although specific terms are employed, they are used in a generic and descriptive sense only and not for purposes of limitation, the scope of the invention being defined in the claim.

10 We claim:

15 An improved multi-section veneer knife adapted to be associated with apparatus for clamping said veneer knife and automatically moving said veneer knife toward a revolving veneer log for cutting sheets of material from said veneer log, said knife comprising a rectangular base section of substantially the length of said veneer log, said base section having a rectangular groove extending along one edge thereof, a plurality of knife sections, each of said knife sections having a rectangular groove extending along one edge thereof, said groove in the knife sections and the groove in the base section being of mating configuration to permit said knife sections to fit in close engagement with said base section, screw means for securing each of said knife sections in close engagement with said base section and in alinement with each other, each of said knife sections having a beveled edge, each of 20 said knife sections having a hardened tip forming a cutting edge, the cutting edge of each of said knife sections being in straight alinement with the cutting edge of the other knife sections, whereby said knife will cut a smooth sheet of material from said veneer log, clamping plates covering the upper and lower surfaces of said base section and also covering a substantial portion of the upper and lower surfaces of the knife sections and a plurality of bolts passing through the base section and the clamping plates for securing the clamping plates to the upper and lower surfaces of the base section.

CLARENCE GOODMAN.
CLAUD T. MILLER.
